CLAIM

The ornamental design for a housing for a communication device or similar articles, as shown and described.

DESCRIPTION

FIG. 1 is a perspective view of an ornamental design of a housing for a communication device or similar articles.

FIG. 2 is a front view.

FIG. 3 is a back view.

FIG. 4 is a left side view.

FIG. 5 is a right side view.

FIG. 6 is a top view; and,

FIG. 7 is a bottom view.

The broken lines shown in the drawings are included for the purposes of illustrating environmental elements only and form no part of the claimed design.
